UNITED STATES PATENT OFFICE

DANIEL I. REITER, OF NEW YORK, N. Y.

SNAP-FASTENER SOCKET

Application filed July 12, 1928. Serial No. 292,221.

This invention relates to an improved snap fastener socket adapted for general application but particularly useful as a part of a rug fastener or other fastener intended to be subjected to the exacting conditions of unusually heavy service.

It is an object of the invention to provide a socket member which may be made from a single piece of metal and which may include a closed cup-like portion adapted to serve as a sounding element, a number of spaced attaching prongs, a channeled portion surrounding the cup-like portion, a number of reinforcing fingers disposed in an alternate relationship with respect to said prongs, and a plurality of resilient stud-engaging fingers which may be cut from the portion of the member surrounding and extending into the outer part of the cupped portion and bent to forms adapted to yieldingly hold an inserted stud, the free ends of said fingers being cut from the material surrounding the stud-receiving portion of the socket member and their fast ends being positioned well within said portion.

In the accompanying drawings illustrating the preferred and a modified form of snap fastener socket embodying the invention,—

Figure 1 is a perspective view of a socket 30 in which the invention is embodied in its preferred form.

Fig. 2 is a face view of the socket illustrated in Fig. 1.

Fig. 3 is a view of the socket in cross-section along the line 3—3 of Fig. 2.

Fig. 4 is a conventional view of a stud adapted to be snapped into an engaging relation with the socket member illustrated in Figs. 1 to 3, inclusive.

Fig. 5 is a cross-sectional view similar to Fig. 3 illustrating a socket embodying the invention in a modified form.

Referring first to Figs. 1 to 4, inclusive, the invention is illustrated as embodied in a snap fastener socket which in its preferred form may be made from a single piece of metal and may include a closed cup-like portion 21, a surrounding channeled portion 22, and a number of marginal attaching prongs

23 extending in spaced relation from the outer wall of the channel.

If desired, the outer wall 24 of the channel may be reinforced or stiffened by means of fingers 25, which may comprise parts of the disk from which the device is made, bent inwardly and downwardly to the base of the channel, as best illustrated in Fig. 3. Such fingers may be disposed in alternate relation with respect to the prongs 23.

The socket member may be provided with flexible stud-engaging fingers 26, which may also comprise parts of the same disk from which other portions of the socket member are formed. In the preferred form illustrated in Figs. 1 to 3, inclusive, these fingers are indicated as having been cut from parts of the structure surrounding and extending into the cup-like portion, the free ends being cut from the part forming the bottom of the channeled portion 22 and their fast ends from the part extending well within the cup-like portion. These fingers are preferably bent inwardly to form the stud-engaging portions 27, thence outwardly as at 28, and thence upwardly as at 29, as best indicated in Fig. 3.

If desired, the stud-engaging fingers 26 may be disposed directly opposite to the reinforcing fingers 25, which may be directed downwardly into the hook-like elements so formed at the ends of the stud-engaging fingers, so as to serve as limiting stops therefor.

The stud 30 diagrammatically indicated in Fig. 4 may be secured to the floor by means of a screw 31 or other appropriate fastening member, and the socket may be secured to a rug or other floor covering by the spurs 28, which may be inserted in the material and bent down against the opposite surface or clinched therein by any suitable tool. The rug or floor covering to which the socket is thus secured may be held in place by applying the socket to the stud so as to cause the latter to be snapped into an engaging relation with the part of the structure immediately surrounding the cup-like portion 21.

It will be obvious that the socket member is adapted for general application and may be secured to articles of fabric, leather, or

other sheet material, and that it may be used with a stud element which may also be secured to leather, fabric, or other sheet material, by means of spurs or other appropriate attaching means.

- 5 In designing the above-described fastener, each part has been so positioned as to best serve its intended function. The prongs are well separated, thereby providing means whereby the socket may be firmly secured to the article on which it is intended to be used. Portions of the metal lying between the prongs have been made use of in the reinforcement of the marginal portion of the socket. The central portion of the disk is made use of as a sounding element adapted to produce a resonant click or snap as the socket is forced into engaging relation with an inserted stud. The closed top of the sounding element serves as a thumb-piece when applying the socket to the stud and prevents the soft material to which the socket may be secured from being forced into the stud-receiving recess and deadening the sound. 10 This is a matter of some considerable importance since customers frequently regard a snap fastener as being inefficient or defective if a sharp snap or click is not produced when the stud and socket are forced into engagement with each other.

Fig. 5 is a sectional view, similar to Fig. 3, of a modified form of the invention, which differs from the form thus far described only in that the stud-engaging fingers 26' are bent inwardly as at 29' instead of being bent outwardly. Other features of this modification correspond with those of the preferred form and need not be specifically referred to.

The invention is not intended to be limited to the forms herein disclosed for purposes of illustration but should be regarded as covering modifications and variations thereof within the scope of the appended claims.

What is claimed is:

- 45 1. A snap fastener socket member made from a single piece of metal comprising a cupped, central, stud-receiving portion, adapted to serve as a sounding element, an annular rim surrounding said cupped portion, and spaced resilient stud-engaging fingers cut partly from said rim and partly from the outer part of the cupped portion and bent to forms adapted to yieldingly hold an inserted stud, the free ends of said fingers being cut 50 from the rim and their fast ends being positioned well within said cupped portion.

2. A snap fastener socket member, as defined by claim 1, having the free ends of its stud-engaging fingers bent slightly into the stud-receiving portion and thence outwardly, and upwardly so as to terminate at points without the stud-receiving portion.

3. A snap fastener socket member made from a single piece of metal comprising a cupped, central, stud-receiving portion,

adapted to serve as a sounding element, a surrounding channeled portion, and resilient stud-engaging fingers having their free ends cut from the material forming the base of the channeled portion and their fixed ends from the material forming the outer part of the stud-receiving portion, said fingers being bent to forms adapted to yieldingly hold an inserted stud.

4. A snap fastener socket member, as defined by claim 3, having attaching prongs extending in spaced relation from the outer wall of the channeled portion.

5. A snap fastener socket member, as defined by claim 3, having reinforcing fingers bent inwardly and downwardly from the outer wall of the channeled portion, to the base of the channel.

6. A snap fastener socket member, as defined by claim 3, having the free ends of its stud-engaging fingers bent slightly into the stud-receiving portion and thence outwardly, and upwardly, so as to form a hook-like element terminating at points within said channeled portion, and having reinforcing fingers bent inwardly and downwardly from the outer wall of the channeled portion with their free ends extended into the hook-like portions of the stud-engaging fingers.

7. A snap fastener socket member, as defined by claim 3, having marginal attaching prongs extending in spaced relation from the outer wall of the channeled portion and reinforcing fingers alternating with said prongs and bent inwardly and downwardly from the outer wall of said channeled portion to the base of the channel, the prong-engaging fingers being bent slightly into the stud-receiving portion, and thence outwardly and upwardly so as to terminate in hook-like elements each so positioned as to receive an end of one of the reinforcing fingers and have its range of free movement limited thereby.

In witness whereof, I have hereunto signed my name.

DANIEL I. REITER.
